UNITED STATES PATENT OFFICE

154,667

DESIGN FOR A HYDRAULIC PRESS UNIT

William C. Denison, Jr., Powell, Ohio, assignor to
The Denison Engineering Company, Columbus,
Ohio, a corporation of Ohio

Application June 12, 1946, Serial No. 130,653

Term of patent 14 years

(Cl. D63—1)

To all whom it may concern:

Be it known that I, William C. Denison, Jr., a citizen of United States, residing at Powell, in the county of Delaware and State of Ohio, have invented a new, original, and ornamental Design for a Hydraulic Press Unit, of which the following is a specification, reference being had to the accompanying drawings, forming a part thereof, in which

Figure 1 is a perspective view of a hydraulic press unit showing my new design; and

Figure 2 is a side elevational view of the hydraulic press unit, shown in Figure 1.

Figure 3 is a front elevational view thereof.

I claim:

The ornamental design for a hydraulic press unit, substantially as shown.

WILLIAM C. DENISON, JR.
